(57) **CLAIM**

The ornamental design for a folding table, as shown and described.

DESCRIPTION

FIG. 1 is a perspective view of the folding table of my new design with the leaves in an open configuration.

FIG. 2 is a perspective view of the folding table of my new design with the leaves in a partially folded configuration.

FIG. 3 is a top plan view of the folding table of my new design as shown in FIG. 1.

FIG. 4 is a bottom plan view thereof.

FIG. 5 is a front elevational view thereof.

FIG. 6 is a rear elevational view thereof.

FIG. 7 is a side elevational view thereof; and,

FIG. 8 is the opposite side elevational view thereof.

1 Claim, 4 Drawing Sheets

FIG. 2

FIG. 1
